UNITED STATES PATENT OFFICE

95,630

DESIGN FOR A SHOE OR ARTICLE OF ANALOGOUS NATURE

Samuel Brietman, Chelsea, Mass.

Application April 4, 1935, Serial No. 56,215

Term of patent 3½ years

To all whom it may concern:

Be it known that I, Samuel Brietman, a citizen of the United States residing at 4 Randalls Avenue, Chelsea, Massachusetts, in the county of Suffolk and Commonwealth of Massachusetts, have invented a new, original, and ornamental Design for Shoe or Article of Analogous Nature, of which the following is a specification, reference being had to the accompanying drawing, forming a part thereof.

In the accompanying drawing Figure 1 is a view, in plan, of a shoe showing my new design; Fig. 2 is a view in perspective, and Fig. 3 is a view in left side elevation.

The dominant feature of my design resides in

the ornamental effect produced by a strip extending as an imitation foxing, from an area forward of the heel on one side of the shoe, rearwardly and upwardly to the back seam and extending as a collar, adjacent the top edge on the other side of the shoe, along said top edge and also along the throat and there terminating on the same side of the shoe as the foxing, and a bow associated with the end of the collar and located on the same side of the shoe as the foxing.

I claim:

The ornamental design for a shoe or article of analogous nature, substantially as shown and described.

SAMUEL BRIETMAN.
